UNITED STATES PATENT OFFICE.

GORDON L. HARRISON, OF SHELBY, MICHIGAN.

DESIGN FOR A TOY OR SIMILAR ARTICLE.

Application filed May 31, 1927. Serial No. 22,226. Term of patent 7 years.

To all whom it may concern:

Be it known that I, GORDON L. HARRISON, a citizen of the United States, residing at Shelby, in the county of Oceana and State of Michigan, have invented a new, original, and ornamental Design for a Toy or Similar Article, of which the following is a specification, reference being had to the accompanying drawing, forming a part thereof, in which:—

Figure 1 is a front view of the toy; and Figure 2 is a side view thereof.

I claim:

The ornamental design for a toy or similar article substantially as shown.

GORDON L. HARRISON.
